US00D907960S

(12) **United States Design Patent** (10) **Patent No.:** **US D907,960 S**
(45) **Date of Patent:** **** Jan. 19, 2021**

(54) **BEVERAGE CONTAINER**

(71) Applicant: **Leapfrog Product Development LLC**,
Chicago, IL (US)

(72) Inventors: **Micaela K. McCabe**, Chicago, IL (US);
Glen C. Gilmore, III, Naperville, IL (US); **Brian M. Clemens**, Burnsville, MN (US); **Steven N. Pinelli**, Ogden Dunes, IN (US); **Richard E. Ellison**, Chicago, IL (US)

(73) Assignee: **Leapfrog Product Development LLC**,
Chicago, IL (US)

(**) Term: **15 Years**

(21) Appl. No.: **29/706,129**

(22) Filed: **Sep. 18, 2019**

(51) LOC (13) Cl. **07-01**

(52) U.S. Cl.

USPC **D7/510; D7/531; D7/532**

(58) **Field of Classification Search**

USPC D7/507, 509, 510, 511, 513, 529, 531, D7/532, 523, 533, 534, 535, 536, 392.1, D7/296.1, 396.2, 300.1, 608, 300, 320, D7/624.1, 624.2; D3/202; D9/501, 502, D9/503, 504, 530, 529, 522, 554, 567, D9/571, 569, 449, 516, 523, 524, 543, D9/565, 575, 556

(57) **CLAIM**

We claim the ornamental design for a beverage container, as shown and described.

DESCRIPTION

FIG. 1 is a top perspective view of a beverage container according to the new design.

FIG. 2 is a bottom perspective view of the beverage container shown in FIG. 1.

FIG. 3 is a front elevation view of the beverage container shown in FIG. 1.

FIG. 4 is a rear elevation view of the beverage container shown in FIG. 1.

FIG. 5 is a left side elevation view of the beverage container shown in FIG. 1.

FIG. 6 is a right side elevation view of the beverage container shown in FIG. 1.

FIG. 7 is a top plan view of the beverage container shown in FIG. 1; and,

FIG. 8 is a bottom plan view of the beverage container shown in FIG. 1.

The broken lines in the drawings illustrate portions of the beverage container that form no part of the claimed design.

1 Claim, 8 Drawing Sheets
